CHEMICAL PUMP

Charles E. Henry and James W. Sullivan,
Santa Barbara, Calif.

Application March 11, 1935, Serial No. 10,449

3 Claims. (Cl. 103—6)

This invention has to do in a general way with apparatus for pumping measured quantities of liquid or semi-liquid material having chemically active properties and is more particularly concerned with improvements in pumps of this general character which are especially adapted for use in delivering a chemical treating reagent into the flow line of an oil well pump for the purpose of breaking an emulsion being pumped. This practice and its purpose are well known to those familiar with the art, and various types of pumps and other injecting apparatus have been devised and used with varying degrees of success for injecting a chemical emulsion breaking reagent into the flow line in the general manner contemplated by this invention.

The chemicals used for this purpose are ordinarily of a heavy consistency and the ingredients therein are of a comparatively active nature so that the usual type of pump with which we are familiar, embodying inlet and outlet valves and packing glands around the moving parts, suffer due to corrosion of the valves and breaking down of the packing glands and are therefore a constant source of trouble.

It therefore becomes a primary object of this invention to produce a pump of the general type described which is characterized by the absence of any packing gland whatever and, further, by the fact that it embodies only a single valve which may be in the nature of an ordinary spring pressed ball check.

It is a further feature of processes, wherein the chemical treating reagent is injected into the flow line, that the quantity of reagent injected is ordinarily relatively small and must be varied depending upon the quantity of the oil being pumped. It is another important feature of this invention that the device is adaptable for adjustment so as to control the quantity of chemical material delivered for each stroke of the apparatus within relatively wide limits. One important feature of the invention is that the device can be adjusted so that the quantity delivered for each stroke may be reduced to almost an infinitesimal amount.

Although various means may be employed for operating the pump contemplated by this invention, we consider it a feature thereof, when the device is used in conjunction with an oil-well pump, that the chemical pump contemplated by our invention is operated by the oil well pump itself so that a reagent is delivered into the flow line for each stroke of the oil well pump. In this way the quantity of treating reagent injected

into the oil can be controlled directly in proportion to the quantity of the oil being pumped.

It is a further object of this invention to produce a device of the class described which is of simple form and construction, may be economically manufactured, has the minimum number of parts, and can be readily taken apart and reassembled for the purposes of inspection and cleaning. 5

The details in the construction of a preferred form of our invention together with other objects attending its production, will be best understood from the following description of the accompanying drawing, which is chosen for illustrative purposes only, and in which 10

Fig. 1 is a diagrammatic elevation illustrating one application of our invention in connection with an oil well pumping apparatus;

Fig. 2 is an enlarged fragmentary sectional elevation illustrating details in the construction of a preferred form of our invention; and 20

Fig. 3 is a plan section taken along the line 3—3 of Fig. 2.

Referring now to the drawing, with particular reference to Fig. 1 which, as pointed out above, 25 shows in a diagrammatic way an oil well pump of conventional construction, reference numeral 11 indicates a standard which has bearings 12 at its upper end to support a walking beam 13. The walking beam 13 is operated in the conventional manner by means of a pitman drive, generally indicated by reference numeral 14, and the front end of the walking beam is connected to a sucker rod 15 which extends downwardly through the upper end of the tubing 16. The 30 tubing 16 communicates with the flow line generally indicated at 17 into which the chemical treating reagent is introduced through a fitting 18 from an outlet pipe or conduit 19. 35

The pump or injecting apparatus contemplated by this invention, which is utilized for the purpose of injecting a treating reagent into the flow line, is generally indicated by reference numeral 20, and the details in the construction of this apparatus are perhaps best illustrated in 45 Figs. 2 and 3, in which reference numeral 21 indicates a tank or container supported upon legs 22 and having a cover indicated at 23. Mounted in the tank or container in any suitable manner is what we may term a stand pipe 24, and 50 in the form of our invention shown in the drawing this stand pipe is shown as having a threaded enlargement 25 near its lower end which is in threaded engagement with an internally threaded flange 26 mounted in the bottom of the container. 55

The conduit 19 is shown as being connected into the bottom portion of the stand pipe 24 as indicated at 27.

It will be observed that the stand pipe 24, which in effect constitutes a portion of the conduit 18, is merely in the nature of a vertically extended open ended pipe which extends a substantial distance into the container. This pipe, which we may also term a cylinder member, has a wall port or a plurality of wall ports indicated at 29 which are situated within the container and establish communication between the interior of the stand pipe 24 and the interior of the container. Reference numeral 38 indicates what we may term a piston or plunger member, reciprocatively mounted within the stand pipe and having a close sliding fit with the interior thereof so as to constitute a plunger and cylinder construction.

20 It will be seen from the construction as so far described that, when the container is filled with the reagent to a point above the lower edge of the port 29, the stand pipe or conduit 24 will be filled to the level of such liquid. As the plunger 25 member 38 is reciprocated from a point above the lower edge of the port 29 to a point below the lower edge of the port 29, (as indicated in dotted lines L) pressure will be applied to the liquid below the ports so as to force the same 30 outwardly through the conduit.

Since the feed into the cylinder member 24 is by gravity, it will be seen that the only valve necessary in the apparatus contemplated by our invention is one which is positioned at some point in the outlet portion of the conduit or between the port 28 and the flow line. In this form of our invention we show such a valve arrangement as being provided in the bottom portion of the stand pipe or cylinder member 24. 35

This valve, which is indicated by reference numeral 30, is shown as being in the nature of an ordinary ball check which is adapted to engage a seat 31 formed in the lower end portion of the stand pipe and is yieldably pressed upwardly toward such seat by means of a compression spring 32, the lower end of which is received in a threaded plug member 33. For the purpose of guiding the valve 30, we show the interior of the valve chamber, which we have 40 indicated by reference numeral 34, as being provided with ribs 35, such construction being best 45 illustrated in Fig. 3.

55 Although various means may be employed for effecting the reciprocation of the plunger member 38, we have, as pointed out above, considered it an important feature that the plunger member be reciprocated in timed relation with the action of the sucker rods which pump the emulsion into the flow line. As a means of accomplishing this result, we provide a lever member indicated at 36 which is shown as being pivoted to one side of the container and extends transversely across the container through a slot 37. The intermediate portion of this lever member 60 36 is connected through a suitable stirrup connection 38 with a reduced rod section 39 on the upper end of the plunger member 38. We prefer to provide a threaded connection here, a lock nut 40 being provided for the purpose of holding the members in proper adjustment. The 65 outwardly extending portion of the lever member 36 is shown in Fig. 1 as being connected through another stirrup connection to the lower end of an actuating rod or bar 42. This bar 42 70 is shown as being formed in sections, the inter- 75

mediate section 42' being carried in guide members 44 and 44' mounted on the standard 11. The upper end of the bar section 42' is positioned immediately below the walking beam 13 and is provided with a cap member or plug member 45 which is threaded to the connection 42' for vertical adjustment, a lock nut 46 being provided to hold the same in proper adjustment. A tension spring 50 is attached to the free end of the lever member 36, such tension spring being also secured to the member 11 or other suitable fixed member so that the lever is normally yieldably held in the position shown in Figs. 1 and 2 where the plunger 38 is in its uppermost position. 50

In operation it will be observed that as the 15 walking beam 13 swings downwardly in the direction of the arrow A it will be brought into engagement with the adjustable cap 45, thereby forcing the lever member 36 and the plunger member 38 downwardly during the continued 20 downward movement of the walking beam after such engagement. The member 45 is adjusted so that this downward movement of the walking beam is effective to push the bottom of the plunger member 38 downwardly to a point below the 25 lower edge of the port or opening 28, the distance beyond the lower edge of the port 28, to which the plunger member is pushed, being the factor which determines the quantity of treating liquid that is injected from the stand pipe or 30 cylinder member 24 into the flow line. Through the arrangement illustrated in Fig. 1 it will be observed that the quantity of liquid injected into the flow line can be easily and quickly adjusted through the medium of the member 45. 35

It will be apparent that the device contemplated by our invention is particularly adapted to pumping various types of reagents which normally have a tendency to attack packing and corrode valves, inasmuch as the device is characterized by the absence of any packing and employs a single valve which is readily accessible and is of the simplest construction. 40

It is to be understood that, while we have herein described and illustrated one preferred form of our invention, and have also illustrated one preferred application or use of the same, the invention is not limited to the precise construction described herein, but includes within its scope whatever changes fairly come within the spirit of the appended claims. 45 50

We claim as our invention:

1. In combination with a well pump having a flow line and a standard supporting a walking beam, means for injecting a treating liquid into the flow line during the operation of the walking beam embodying: a tank adjacent to said standard adapted to contain treating liquid; a stand pipe in the bottom of said tank having a wall port communicating with the interior of said tank; a downwardly opening check valve in said stand pipe below the port therein; a conduit connecting the bottom of said stand pipe with said flow line; a piston member in said stand pipe; a lever member pivotally mounted above said plunger and adapted to impart reciprocation thereto; yieldable means mounted on said standard normally supporting said plunger with its lower end above the bottom of said port; and means comprising a push rod slidably mounted on said standard having its lower end secured to said lever member and having its upper end adapted to be engaged by said walking beam for swinging said lever member to push the bottom of said piston 75

member downwardly below the lower edge of said port.

2. In combination with a well pump having a flow line and a standard supporting a walking beam, means for injecting a predetermined quantity of treating fluid into the flow line during the operation of the walking beam embodying; a tank adjacent to said standard adapted to contain treating liquid; pumping means within said tank; an adjustable slideable bar mounted on the walking beam standard and adapted to be actuated by the walking beam; means for yieldably holding said bar at its upward limit of extension; a lever connecting said bar with said pumping means inside the tank; and a conduit connecting said pumping means with said flow line.
3. In combination with a well pump having a flow line and a standard supporting a walking beam, means for injecting a predetermined quantity

of treating fluid into the flow line during the operation of the walking beam embodying; a tank adjacent to said standard adapted to contain treating liquid; pumping means within said tank; an adjustable slideable bar member mounted on the walking beam standard, comprising a lower section, an intermediate section, and an upper cap member section threaded into the intermediate section and adapted to be periodically engaged by said walking beam; means for adjusting said cap member, means for yieldably holding said bar at its upward limit of extension; a lever mounted on said tank connecting said bar with said pumping means within said tank; and a conduit connecting said pumping means with said flow line.
